UNITED STATES PATENT OFFICE.

CHARLES H. LINDENBERG, OF COLUMBUS, OHIO.

DESIGN FOR A REGALIA-COLLAR.

SPECIFICATION forming part of Design No. 34,386, dated April 16, 1901.

Application filed March 23, 1901. Serial No. 52,663. Term of patent 14 years.

To all whom it may concern:

Be it known that I, CHARLES H. LINDENBERG, a citizen of the United States, residing at Columbus, in the county of Franklin and State of Ohio, have invented and produced a new and original Design for Regalia-Collars, of which the following is a specification, reference being had to the accompanying drawing, forming part thereof, in which is represented a face view of my newly-designed collar.

As shown in the drawing, the leading or material features of my design consist in a regalia-collar, upon the front faces of which appear the oppositely-located and successively-arranged representations of three links, flags, and shield-like bodies. Adjacent to the edges of the collar and extending about the same is a binding *a* of contrasting color with the body, and the connected links *b* and shield-like bodies *c* have a filling of a contrasting color with the face of the collar. In the upper por-

tion of each of the shield-like bodies is the representation of an eye surrounded by light-rays, and each of said shield-like bodies *c* has its sides provided with an inner border of suitable scroll or leaf work. The flags *d*, which appear between the representations of the connected links *b* and the bodies *c*, are shown as caught together at the centers of their lengths by a fanciful ring or wreath *e*.

Having described my invention, what I claim as new, and desire to secure by Letters Patent, is—

The design for a regalia-collar as herein shown and described.

In testimony whereof I have signed my name to this specification in the presence of two subscribing witnesses.

CHARLES H. LINDENBERG.
